COIN HOLDER

Åke Albin Hultberg, Aspudden, Sweden

Application January 25, 1950, Serial No. 140,369
In Sweden January 28, 1949

3 Claims. (CL 133-6)

1

Coin-holders are employed for the storage of coins in such a manner that the latter are easily accessible and can be fed out in assorted values. I have previously proposed a coin-holder of this kind comprising a casing with a number of pockets, recesses or cavities, each dimensioned or fitted to the size of a certain species of coin and containing a spring for pressing the coins arranged in a pile, towards a top part or cover of the casing. An opening or slot is provided for feeding out the uppermost coin in each pile.

The main object of my present invention is to improve coin-holders of this general type, particularly to facilitate feeding out of the coins. I have found that in the case of small coins such as 10-cent and 25-cent pieces difficulties are encountered in feeding them out from the casing (particularly in the case of a new coin) on account of the friction between the finger and coin being insufficient as compared with the friction between the said coin and the underlying coin.

It is also an object of the invention to arrange means for retaining the uppermost coin in the pocket until it is desired to push it out from the pocket.

A further object of the invention is to provide a resilient ejecting member or a spring at each pocket adapted to cooperate with the edge of the uppermost coin in the pocket, and to arrange a projection or stop means to prevent the coin from being released from the pocket unintentionally.

A still further object of the invention is to render the coin-holder suitable for use as a roulette or the like by providing the casing of the coin-holder, which may have the form of a flat box, at one or both of its flat sides with a central projection or pin adapted to serve as a rotating pivot and by means of which the entire coin-holder may be set in rotation when the projection is placed on a suitable base.

A still further object of the invention is to arrange a washer or plate of a particular colour in each pocket and to indicate on this washer or plate the value of the coins to be placed in each pocket.

One embodiment of a coin-holder according to the invention is illustrated in the accompanying drawing in which:

Fig. 1 is a cross-section of the coin-holder along the line 1—1 in Fig. 2,

Fig. 2 is a plan view of the coin-holder without coins, whilst

Fig. 3 shows a section of a detail on a larger scale on line 3—3 in Fig. 2.

2

The coin-holder consists of a casing 1 of transparent or opaque material such as plastic or a synthetic resin, with cylindrical pockets, cavities or recesses 7, 8, 9, 17, 18, 19 of different sizes corresponding to the size of the coins 6 to be stored in the casing. At the top the recesses are provided with a cover or top part 2 having feed openings 2a which, however, have a smaller diameter than the corresponding recesses 7, 8, 9, 17, 18, 19, and the coins contained therein so that the coins inserted in the recesses are prevented from falling out unintentionally. The casing is also provided with a bottom 3 and inside each recess 7, 8, 9 there is a spring 4 (Fig. 1) which abuts against the bottom 3 and a washer or plate 5a, 5b, 5c, 5d, 5e, 5f. Under the action of said spring the coins are pressed towards the surrounding edge portion of the top part 2 and thus the said coins will be retained in their recesses. Feeding out of the coins is effected by withdrawing the desired number of coins sideways with the finger, whereby the pressure of the spring 4 is overcome. To this purpose each opening 2a communicates with a lateral slot 2b. This method of feeding out can be undertaken with the thumb of the same hand in which the coin-holder is held.

To assist in preventing the uppermost coin in each coin pocket or recess from falling out, each opening 2a is provided with an inwardly projecting stop or flange 11 (Fig. 3) which extends along a desired part of the circumference of the opening 2a and cooperates with the customary raised edge along the periphery of the uppermost coin 6. In addition, a spring 12 of any suitable material, such as a spring plate or strip, is fixed at the rear part of the feed opening 2a to assist in feeding out the coin through the slot 2b. This spring 12 extends obliquely for a short distance towards the interior of the coin pocket and engages the back edge of the uppermost coin 6. As soon as the coin is pressed down against the action of the previously mentioned spring 4, the locking engagement between the raised edge of the coin and the projection 11 is released and at the same time the coin is pressed outwards by the spring 12. In view of the fact that this spring engages the lower edge of the coin in the position of rest as shown in Fig. 3, the spring will not exercise any detrimental tendency to feed out the coin until the latter has been pressed down. The whole arrangement is extremely effective and simple. The spring 12 may be secured to the top part 2 or to an adjacent part of the casing 1.

The washers 5a-5f may, if desired, be made of coloured material (different colour than the coins) to enable them to be distinguished clearly from the actual coins. Furthermore, the washers may be provided with suitable text indicating the species of coin for which the coin pocket in question is intended.

A projection or pivot 10 may be secured or formed centrally to the top side of the cover 2 and/or to the bottom 3 of the casing. When the casing (without coins) is placed on a base (such as a table) with this projection turned downwards, the casing can be set in rotation around the projection and in this way the device may be employed as a roulette or other round game, whereby the value indications on the washers 5a-5f serve as roulette markings. The game is played in such a way that the player observes which of the washers 5a-5f on the rotating casing that stops right in front of any given index, such as a match, set out on the base and then the value indicated on this washer is noted as score.

The casing may consist of metal, plastic material or other substance, preferably of transparent character. The bottom and sides may, if desired, be constructed in one piece and the top part 2 may be constructed separately of metal or plastic material and attached to the casing by suitable means such as rivets 13 (Fig. 2). The top part may also be constructed in one piece with the casing itself. The bottom 3 may also be made as a separate member attached to the remaining part of the casing.

The shape and size of the coin-holder may be varied according to the number of coins of different values it is required to contain. Thus, the invention is not limited to the form of construction shown.

What I claim is:

1. A coin holder comprising, in combination, a casing formed with at least one recess having an open end and adapted to house a pile of coins, said casing being also formed with a coin dispensing slot located adjacent to said open end of said recess and communicating with the same; spring means located in said recess for urging coins toward said open end of the same; a top part secured to said casing and having a rim including at least one recessed rim portion projecting over a portion of said recess and adapted to retain coins in the same against the action of said spring means, said recessed rim portion being provided with a projection projecting into said recess and adapted to engage a raised coin rim on the outermost coin located at said open end of said recess; resilient means located in said recess adjacent to said open end of the same and adapted to urge said outermost coin toward said dispensing slot and against said projection of said recessed rim portion, said projection preventing dispensing of said outermost coin through said dispensing slot, an outermost coin being dispensed by manually pressing the same into said recess against the action of said spring means and of said resilient means so as to disengage said coin rim from said projection on said recessed rim portion for moving said outermost coin through said dispensing slot.

2. A coin holder comprising, in combination,

a casing formed with at least one cylindrical recess having an open end and adapted to house a pile of coins, said casing being also formed with a coin dispensing slot located adjacent to said open end of said recess and communicating with the same; spring means located in said recess for urging coins toward said open end of the same; a top part secured to said casing and having a rim including at least one recessed rim portion projecting over a portion of said recess and adapted to retain coins in the same against the action of said spring means, said recessed rim portion being provided with an arcuate projection projecting into said recess and adapted to engage a raised coin rim on the outermost coin located at said open end of said recess; leaf spring means located in said recess adjacent to said open end of the same and oppositely said dispensing slot and extending obliquely into said recess so as to engage the bottom edge of said outermost coin and to urge said outermost coin toward said dispensing slot and against said arcuate projection of said recessed rim portion, said projection preventing dispensing of said outermost coin through said dispensing slot, an outermost coin being dispensed by manually pressing the same into said recess against the action of said spring means and of said leaf spring means so as to disengage said coin rim from said projection on said recessed rim portion for moving said outermost coin through said dispensing slot.

3. A coin holder comprising, in combination, a casing formed with a plurality of cylindrical recesses having an open end and adapted to house a pile of coins, said casing being also formed with a plurality of coin dispensing slots, each slot located adjacent to said open end of one recess and communicating with the same; spring means located in each recess for urging coins toward said open end of the same; a top part secured to said casing and having a rim including a plurality of recessed arcuate rim portions, each rim portion projecting over a portion of one recess and adapted to retain coins in the same against the action of said spring means, each recessed rim portion being provided with a projection projecting into one recess and adapted to engage a raised coin rim on the outermost coin located at said open end of said recess; resilient means located in one recess adjacent to said open end of the same and adapted to urge said outermost coin toward said dispensing slot and against said projection of said recessed rim portion, said projection preventing dispensing of said outermost coin through said dispensing slot, an outermost coin being dispensed by manually pressing the same into said recess against the action of said spring means and of said resilient means so as to disengage said coin rim from said projection on said recessed rim portion for moving said outermost coin through said dispensing slot.
